US00D769740S

(12) **United States Design Patent** (10) Patent No.: **US D769,740 S**
Legros (45) Date of Patent: **** Oct. 25, 2016**

(54) **WRIST WATCH**

(71) Applicant: **LINKOO TECHNOLOGIES**, Lyons (FR)

(72) Inventor: **Lionel Legros**, Lyons (FR)

(**) Term: **15 Years**

(21) Appl. No.: **35/500,068**

(22) Filed: **Jul. 9, 2015**

(80) **Hague Agreement Data**

Int. Filing Date: **Jul. 9, 2015**

Int. Reg. No.: **DM/086963**

Int. Reg. Date: **Jul. 9, 2015**

Int. Reg. Pub. Date: **Jul. 31, 2015**

(51) **LOC (10) Cl.** **10-02**

(52) **U.S. Cl.**

USPC **D10/32**

(58) **Field of Classification Search**

USPC D10/30-32, 38-39, 21-22, 126, 104.2

CPC G04C 1/00; G04G 9/00
